Dec. 1731

Robert S. Stanton, of New York, N.Y.
Letter Patent No. 1731, dated Mar. 3. 1863.

The schedule referred to in these Letters Patent and making part of the same.

To all whom it may concern:

Be it known that I, Robert S. Stanton, of the City, County, and State of New York, have invented and produced a new pattern or design for the shape and configuration of metallic skates; and I do hereby declare that the following is a full and exact description of the same.

The foot plate is composed of Iron, Steel, Brass or other metal, japanned, painted, polished or galvanized and formed to the shape of the sole of the foot, flat at the heel, rising under the instep, depressed again with a gradual curve for the ball of the foot and again curving upwards as per annexed drawings A, with the heel and toe pieces or standards cast (or in case of wrought iron forged) in iron, brass, or other suitable metal B. The standards are placed one under the heel with a screw E, passing through and projecting from the heel of the foot plate, the other under the ball and toe joint of the foot, with a flat headed screw f, passing through the centre of the foot plate and into the upright part of the standard, they are composed of one upright piece of metal with branching arms a. The heel and toe pieces is formed to connect the foot plate A, to the runner C, and are grooved out at the lower ends of the uprights that they may straddle the runner C, and to be attached thereto by rivets at the points d. The runner is the ordinary skate runner cast or forged in the usual manner from iron or steel except that it has a higher sweep to meet the elevation of the toe of the foot plate A, and comes in contact with the foot plate A, at and under the extreme point of the toe all in conformity with the drawings herewith annexed, the whole forming what I claim as a design for a metallic skate new in form, elegant in shape.

Witnesses.
